No Drawing. Original application March 13,
1944, Serial No. 526,336. Divided and this ap-
plication February 20, 1945, Serial No. 578,950.
In Great Britain November 27, 1942

10 Claims. (Cl. 175—315)

1

This application is a divisional from our co-pending application Serial No. 526,336 filed March 13, 1944.

It is known, for many purposes, to replace glycerol or ethylene glycol by aqueous solutions of sodium lactate.

These solutions have, however, the disadvantage that they attack certain metals, especially aluminium or its alloys and corrode the surfaces especially at those points at which two different metals—e. g., aluminium and brass—are joined together.

It is an object of the present invention to provide a solution which can be used as a substitute for glycerol and which will not possess the disadvantages attendant upon the use of sodium lactate.

When a solution of dl-beta-hydroxybutyric acid is neutralised in the usual way by means of an alkaline hydroxide or carbonate, the pH of the solution thus obtained falls, on standing, due to the hydrolysis of anhydrides of the acid. Even apparently pure sodium dl-beta-hydroxybutyrate may develop acidity in solution.

Liquid compositions may, for example, be obtained by adding to a solution of dl-beta-hydroxybutyric acid, a suitable alkali (e. g. sodium or potassium hydroxide, carbonate or bicarbonate) the amount of which is such that the pH of the resulting solution remains within the pH ranges indicated. If desired, the addition of alkali can take place at raised temperature, e. g. 40°—110° C., at which hydrolysis of the anhydrides is rapid.

A small proportion of the above alkalis may be replaced by organic bases, e. g. triethanolamine or alkaline-reacting salts, e. g. trisodium phosphate.

The liquid composition may contain, with advantage, small amounts, e. g. up to 3% by weight, of alkaline phosphates, silicates or chromates. Phosphates of amines, such as triethanolamine, which have been previously proposed as stabilisers for polyhydric alcohols, are particularly suitable for this purpose.

It is a further object of the invention to provide a method of minimising the corrosion of a corrodible metal, as hereinafter defined, when in contact with water or an aqueous solution of an electrolyte.

The aqueous solutions of sodium or potassium dl-beta-hydroxybutyrate can advantageously be used instead of glycerol in many, if not all, of its various applications and, at the same time, these solutions possess the advantage that they

2

do not cause any practical corrosion of parts formed of aluminium or alloys in which aluminium predominates nor do they cause any corrosion of parts in which aluminium is in contact with metals which themselves are resistant to corrosion by water; this last fact is most surprising since these dl-hydroxy-butyrate must be regarded as being electrolytes.

By the expression "corrodible metal" used 10 herein, is meant copper, brass, iron or nickel or alloys containing these metals, hard or soft solders, aluminium or alloys in which aluminium predominates. Where corrodible metals other than aluminium or aluminium are concerned, the 15 pH of the said dl-beta-hydroxybutyrate solutions is, according to a feature of the invention regulated to fall within the range of 7.0 to 8.5, preferably 7.5 to 8.5.

Solutions containing 50% by weight of the 20 salts do not solidify at temperatures as low as —50° C.

Solutions up to 80% by weight can be boiled 25 without decomposition and such solutions can be used in containers formed of metals of the character of aluminium as the containers are not corroded. The same remark applies to containers which are lined with enamel. Such linings are corroded by sodium lactate which regularly develops an alkaline reaction.

30 The fact that sodium and/or potassium dl-beta-hydroxybutyrate reacts neutral in aqueous solution makes it especially suitable for electrical purposes, e. g. in electrolytic condensers. In electrolytic condensers sodium and/or potassium dl-beta-hydroxybutyrate is particularly useful, as 35 it can be made into solutions of high viscosity which have considerable hygroscopicity which prevents the electrolyte from drying out.

In the manufacture of the so-called dry electrolytic condensers it has previously been proposed to use a variety of salts in aqueous solution as the electrolyte to which have been added thickening agents as well as other agents designed to prevent the electrolyte becoming useless by evaporation.

45 The production of an electrolyte in this way is tedious and costly. It has also been proposed to use metallic lactates as electrolytes for this purpose. The lactates do not require the addition of thickeners and are sufficiently hygroscopic to avoid the necessity of adding substances 50 to prevent evaporation of water.

We have now found that concentrated aqueous 55 solutions of sodium and/or potassium dl-beta-hydroxybutyrate adjusted so that their pH remains within the range 6.0—8.5 and preferably

within the range 6.0-7.5, are especially suitable for use as electrolytes in the manufacture of electrolytic condensers. We have found that these salts of dl-beta-hydroxybutyric acid possess an advantage over the corresponding salts of lactic acid in that they are much less corrosive towards the aluminium foils used in the condensers.

According to the invention therefore, there is provided an electrolytic condenser comprising a plate, foil or the like of, or containing a predominating proportion of, aluminium and electrolyte consisting of an aqueous solution of sodium and/or potassium dl-beta-hydroxybutyrate whose pH has been adjusted to remain permanently within the range of 6.0 to 8.5; preferably the pH range lies between the values 6.0 and 7.5 or, better, between 6.8 and 7.4.

Concentrated solutions of sodium and/or potassium dl-beta-hydroxybutyrate are of high viscosity so that the addition of thickening agents or hygroscopic substances to prevent evaporation is not necessary.

It is known that sodium lactate solutions become more and more alkaline particularly when in contact with aluminium surfaces and corrosion of the aluminium takes place through an attack on the anodic oxide layer on the surface of the aluminium, which layer is necessary for the functioning of electrolytic condensers.

We have found that solutions of sodium and/or potassium dl-beta-hydroxybutyrate prepared in the above-described manner do not attack aluminium and the pH of their solutions does not increase with age nor do such solutions cause de-

struction of the protective oxide film in the condensers.

The electrolyte solution contains, preferably, more than 40% by weight of the salt.

Solutions of more than 40% strength do not crystallise at temperatures above -20° C. and it is a special advantage of electrolytic condensers made according to our invention that they do not deteriorate at low temperatures such as are experienced, for example, in aircraft.

Compared with ethylene glycol, which has been used extensively in the manufacture of electrolytes for condenser the solutions of the said salts of dl-beta-hydroxybutyric acid possess the advantage of non-toxicity and non-inflammability.

It is, of course, within the scope of our invention to employ, as electrolytes, sodium and/or potassium dl-beta-hydroxybutyrate solutions which have been modified by the addition of other ingredients such as gelatins, glycerol or ethylene glycol.

A special advantage in the use of sodium and/or potassium dl-beta-hydroxybutyrate solutions lies in the fact that they can be readily obtained from distilled dl-beta-hydroxybutyric acid and thus be freed from inorganic impurities such as chloride, which are a frequent cause of deterioration in electrolytic condensers.

The advantage of sodium dl-beta-hydroxy-

butyrate over sodium lactate is shown in the following comparative examples:

Tests were carried out with equal amounts of 50% by weight solutions of both salts by heating test-pieces to 95° C. for 50 hours in contact with the solutions.

10	Material tested	Loss in grams per square metre per hr.	
		Sodium lactate	Sodium dl-beta-hydroxybutyrate
15	1 Aluminum	7.0	0.0074
	2 Aluminum alloy filing (Dur-alumin (registered trade mark)).	Entirely dissolved after 5 hours.	0.070
	3 Aluminum in contact with brass.	5.5	0.0009

20 In the third test, sodium lactate attacked not only the aluminium but also the brass, which remained entirely unaffected in the test with sodium dl-beta-hydroxybutyrate.

During the tests in the sodium lactate solution 25 25, the hydrogen evolved was visible to the naked eye.

A further series of tests were conducted with pieces of metal and metal alloys having a surface of 1100 mm.². The figures given show the loss 30 of weight (or where + is shown the increase in weight) in mgm. per test piece per 24 hours. The test pieces were immersed in the solution (whose composition is given in the table in percentage by weight) at a temperature of 80-90° C. and 35 weighed at 24 hour intervals.

	pH	Aluminum	Aluminum brass	Copper	Brass	Copper-brass-solder	Soft Solder	Mild Steel-brass-solder
1	Sodium lactate (30%)	6.5	65					
2	Sodium hydroxybutyrate (27.5%)	6.8	nil	nil				
3	Sodium hydroxybutyrate (27.5%) + Triethanolamine phosphate	7.8	nil	nil	+0.5	0.9	1.0	10.0
4	Sodium hydroxybutyrate (27.5%) + Trisodium phosphate	8.4	nil			0.7	0.2	0.2
5	Sodium hydroxybutyrate (27.5%)	8.0	nil			0.4		0.2

Tests have also been carried out in which an aluminium sheet and a mild steel-soft solder-brass couple were each subjected for 24 hours to 50 the action of a 30% by weight aqueous solution of sodium dl-beta-hydroxybutyrate at 95° C. The following table shows the loss of weight in gms. per sq. metre over that period.

55	Mild steel-soft solder-brass	Aluminum
pH 6.8	1.12	None
pH 8	None	Do.
60 pH 7.6 (+triethanolamine phosphate (1.2%))	do	Do.
pH 7.8 (+trisodium phosphate (0.5%))	do	Do.

Although water is the preferred solvent for use in making up the liquid composition, it may be partly replaced by organic solvents capable of dissolving the sodium and potassium salts of dl-beta-hydroxybutyric acid, e. g. alcohol.

70 A further advantage of sodium and/or potassium dl-beta-hydroxybutyrate is that it can be easily synthesised from acetaldehyde and obtained free from impurities e. g. inorganic salts.

It is also possible to provide a process for the direct preparation of neutral and very pure solutions of the salt. Accordingly, dl-beta-hydroxybutyric acid, e. g. as obtained by the oxidation of

5

acetaldol according to our prior application Serial No. 511,120, now Patent No. 2,411,700, is neutralised with aqueous sodium or potassium carbonate or aqueous sodium or potassium hydroxide and the solution evaporated to dryness, preferably in *vacuo*. The residue may, if desired, be recrystallised from alcohol, and finally dissolved in the desired amount of water. It is, however, also possible to wash the solid residue with cold alcohol, though the recrystallisation from alcohol gives a still purer and exactly neutral product. The dl-beta-hydroxybutyric acid used may have been previously distilled in *vacuo* in order to facilitate the production of a pure product.

In contrast to the case of sodium lactate, the direct oxidation of acetaldol to the acid, as indicated above, offers the further advantage that it is possible to obtain a substantially water-free acid and this merely requires to be diluted with the necessary amount of water and treated with the required alkali in order to give the desired solutions. Thus the arduous evaporation of water from primary dilute solutions, such as are unavoidably obtained in the manufacture of sodium lactate and which leads to the formation of deeply coloured solutions, is avoided. Unlike sodium lactate the sodium or potassium salt of the dl-beta-hydroxybutyric acid will form solid well defined crystals by the simple evaporation of its aqueous solutions and, therefore, it can readily be purified by dispersing it in a solvent in which said salt is insoluble or only sparingly soluble.

We have discovered that there is yet a further advantage in that if a solution of the dl-beta-hydroxybutyric acid in water is prepared with a concentration greater than 35% by weight of the acid, the process for the preparation of the sodium salt is made very much simpler since we have discovered that with such solutions it is possible to add an excess of sodium or potassium carbonate since the excess unreacted sodium or potassium carbonate will not dissolve, or only very slowly dissolves, in the aqueous solution of sodium dl-beta-hydroxy butyrate; thus all that is necessary is to prepare the sodium salt by the addition of sodium carbonate and filter, or decant off, the solution from the excess residual sodium carbonate.

The crystals of the sodium salt are soft in character and they do not tend to block pipe lines or conduits through which they may be passed when the solution is used under conditions in which crystallisation is likely to take place, although under normal conditions crystallisation does not occur.

If, however, the possibility of crystallisation is present and is thought to be undesirable, it may be counteracted, without detriment to the other properties of the solution, by the addition of small amounts of the lower sugars; we have found that the addition of these lower sugar substances inhibits the crystallisation of solutions of the sodium salt. It is therefore a further additional feature of the invention to provide aqueous solutions of the sodium dl-beta-hydroxy butyrate containing small amounts of the lower soluble carbohydrates or substances derived therefrom. We find that the oxidation of technical acetaldol is a particularly advantageous method of obtaining the desired solutions of the sodium salt since acetaldol contains such substances as will form, in the final oxidation mixture, small quantities of the lower sugars and this invention therefore contemplates the use of such solutions for the formation of the sodium salt of the invention from which the lower

6

sugar compounds have not, or have only partially, been removed and in which the pH value is preferably maintained between 6.5 and 7.0 in order to prevent the formation of colour in the solution with age or with use.

We find that solutions of sodium dl-beta-hydroxybutyrate are more effective weight for weight as freezing point depressants than are sodium lactate or other anti-freeze agents.

10 This may be seen from the following table in which there is set out the weights per cent of various anti-freeze agents necessary to reduce the freezing point of an aqueous solution to a value of -20°C .

	Anti-freeze agent	Percentage by weight
20	Glycerol	45.0
	Ethylene glycol	38.0
	Sodium lactate	32.5
	Sodium dl-beta-hydroxybutyrate	27.5

25 It has been observed that the solutions of the present invention develop, at low temperatures, a lesser viscosity than that of another anti-freeze solution of the same freezing point, i. e. the solutions are less viscous at low temperatures than the corresponding glycerol anti-freeze solutions whilst at high temperatures the viscosity of the 30 solutions is little different from that of water.

The solutions of the present invention have a boiling point only a little higher than that of water, for example, a 50% by weight solution has 35 a boiling point of only 108°C ; the heat capacity of solutions having a freezing point of -20°C . or less is high i. e. the specific heat of such solutions is about 0.9 calorie per gram. The solutions are also very stable to heat and solutions of from 40 10-40% by weight remain neutral even if boiled for many hours whereas solutions of sodium lactate develop an alkaline reaction which becomes more pronounced as heating continues.

Where substantially colourless solutions of 45 sodium dl-beta-hydroxybutyrate are desired it is preferable to remove any aldehyde or high molecular weight compounds by treating the aqueous solution of the dl-beta-hydroxybutyric acid with active carbon and/or hydrogen peroxide or other 50 bleaching agent, such as basic lead acetate, which does not attack the acid and thereafter neutralise the acid with alkali as already described. It is also advisable to heat the reaction mixture, obtained by the oxidation of acetaldol, with live 55 steam until all volatile aldehydic substances are removed and thereafter to add alkali to form the sodium dl-beta-hydroxybutyrate. It is observed that the acid remains in the still unchanged throughout the steam distillation.

60 What we claim is:

1. An electrolytic condenser comprising an electrode of a material comprising essentially aluminium and an electrolyte consisting of an aqueous solution of a salt of the group consisting of the sodium and potassium salts of dl-beta-hydroxybutyric acid, the pH of said solution being substantially permanent between 6.0 and 8.5.

2. An electrolytic condenser according to claim 70 1 wherein the pH of the electrolyte solution is between 6.0 and 7.5.

3. An electrolytic condenser according to claim 1 wherein the pH of the electrolyte solution is between 6.8 and 7.4.

4. An electrolytic condenser according to claim 75

1 wherein the electrolyte solution contains not less than 40% by weight of said salt.

5. An electrolytic condenser comprising an electrode containing at least a predominating proportion of aluminium and an electrolyte consisting of an aqueous solution of an alkali metal salt of dl-beta-hydroxybutyric acid whose pH is substantially permanent between 6.0 and 8.5.

6. An electrolytic condenser according to claim 5 wherein the pH of the electrolyte solution is 10 between 6.0 and 7.5.

7. An electrolytic condenser according to claim 5 wherein the pH of the electrolyte solution is between 6.8 and 7.4.

8. An electrolytic condenser according to claim 5 wherein said electrolyte solution contains not less than 40% by weight of sodium dl-beta-hydroxybutyrate.

9. An electrolytic condenser according to claim 5 wherein said electrolyte solution contains not less than 40% by weight of potassium dl-beta-hydroxybutyrate.

10. An electrolytic condenser comprising an electrode of a corrodible metal and an electrolyte

consisting of an aqueous solution of an alkali metal salt of dl-beta-hydroxybutyric acid whose pH is substantially permanent between 6.0 and 8.5.
